ACHILLE DRYEN, OF LONDERZEEL, BELGIUM.

PUMP.

1,327,423.

Specification of Letters Patent.

Patented Jan. 6, 1920.

Application filed February 11, 1918. Serial No. 216,643.

To all whom it may concern:

Be it known that I, ACHILLE DRYEN, a subject of the King of Belgium, residing at Londerzeel, in the Kingdom of Belgium, have invented certain new and useful Improvements in Pumps, of which the following is a specification.

This invention relates to pumps and more particularly to pumps of that class which 10 is used to force viscous solutions through capillary orifices as is the case, for instance in the manufacture of artificial silk.

As is known, it is necessary in the manufacture of artificial silk in order to secure a 15 regular weight of thread per unit of length, that the pump forcing the solution of cellulose through the capillary orifices, discharge a uniform quantity of solution.

This control of the output is generally effected by means of a pump developing per 20 unit of time a constant volume and delivering an equal volume of solution of cellulose through the capillary orifices, whatever may be the viscosity of the solution and the state 25 of the capillary orifices or of the filter through which the solution has been passed before reaching the capillary orifices.

Practically, it is very difficult to secure a 30 constant output by means of the pumps actually used.

Rotating pumps with gears cannot secure a constant output in view of their important dead-spaces; piston-pumps provided with valves (either actuated by springs or not) have also a very variable output on account 35 of the resistance which is opposed by the viscosity of the solution to the rapid operation of the valves. For this reason use is generally made of pumps provided with a positively operated distributor having, at each 40 moment, a given position relatively to the piston of the pump. The use of this class of pumps, however, causes great difficulties, arising from the the incompressibility of the 45 solution of cellulose.

In fact, in order that each pump may give an invariable volumetric output, it is necessary that the distributor possess a perfect tightness on account of the fact that a pump 50 of this kind has to deliver only a few hundreds of cm^3 per hour and that a manu-

facturer of artificial silk generally uses many thousands of these pumps which must all have the same volumetric output.

In order to obtain such a tightness it is 55 necessary that no back flow can take place through the distributor from the high pressure side to the low pressure side, which flow can easily occur if it is taken in consideration that, with collodion for instance, the 60 difference of pressure between the two sides may vary from 40 to 50 atmospheres. To avoid such flow, the distributor must possess overlapping parts at both sides which results in a compression of the solution of 65 cellulose during the time that the distributor reverses the communications, while being approximately in its mean position. But as the solution is incompressible, the pressure rises in the cylinder, thus throwing great 70 strains on the driving motor with the result that a part of the solution of cellulose is expelled through one or the other joint of the distributor, or of the piston or of the exterior packing.

As a consequence thereof independently of the variation of the volumetric output and of great strains, a part of the solution of cellulose is disposed in the joints and on the friction surfaces; this solution on coagulating and hardening, increases the friction and, as a result, the pump is soon out of 75 order.

One object of my invention is to avoid 80 said inconveniences.

Another object is to provide for all the 85 pumps of one installation a driving means which, although being very simple, will satisfy all the above stated requirements.

Referring to the annexed drawing: 90 Figure 1 shows a horizontal section of the pump constructed according to my invention, the distributor being in its mean position.

Fig. 2 is a side elevation, on a reduced 95 scale, showing the simultaneous driving of the several pumps of a spinning machine.

In the drawing, 1 is the distribution chest, 2 the cylinder of the pump.

The slide valve 3 is of the ordinary D 100 type, although any other form may be adopted; the type shown has an advantage

in that by the difference of pressure acting upon the upper face and upon the lower face of the slide valve, this latter is strongly pressed upon its seat. The solution of cellulose, entering through 4 into the distribution chest is conducted, according to the position of the distributor, through the channels 5 or 6 to the one or other face of the piston 7; then, when the slide valve has reversed the 10 communications, it is forced through channel 8 of the slide valve toward the outlet 9.

In order to impart the necessary tightness to the piston, it has been sufficiently lengthened so as to avoid any possibility of 15 leakage of the solution; the piston however may be provided with rings or with a packing of a suitable kind.

The tightness of the rods of the piston and of the distributor is secured by a packing 11 pressed between a ring 10 and a stuffing box 12 tightened by a nut 13.

Movement is given to the distributor and to the piston of the pump by aid of two independent rods 14 and 15 to which the rods 25 of the distributor and of the piston are connected without articulations by means of catches 16 which are keyed on the rods 14 and 15.

The movement of the rods 14 and 15, 30 which is identical to that of the parts which are driven by them, is controlled in such a manner that the rod 15, driving the piston 7 remains unmoved at the end of each stroke while the rod 14, driving the distributor and 35 having with regard to the rod 15, a lead in relation to the characteristics of the distributor, still moves forward.

In the example shown, the movement of the rods 14 and 15 is produced by rollers 17 40 and 18 (Fig. 2) moving in slots 19 and 20 provided in blocks 21 and 22 to which blocks a reciprocating movement is transmitted by cranks and connecting rods.

In order to maintain the rod 15, driving 45 the piston at rest at the end of each stroke, the slot 19 of the block 21 is provided at both ends with a part 23 parallel to the direction of movement of the block in such a manner that at the moment the roller 17 is 50 in contact with this part of the slot, the rod 15 remains absolutely unmoved.

I do not limit myself to this specific mechanism, however, as other means for accomplishing the same result may be employed.

55 As shown in Fig. 2, the rods 14 and 15 extend the whole length of the spinning machine and operate, through the catches 16 all the pumps of said machine, said pumps being arranged coaxially or in a line. The 60 solution of cellulose leaving the pump, is directed to a nozzle or to a pipe upon which the capillary orifices are mounted.

On the pipe leading to the nozzle or to the nozzle-pipe is branched an air vessel in 65 which the forcing pressure is maintained.

Owing to the elasticity of the air contained in this vessel, the solution of cellulose contained in the lower part of said vessel feeds the nozzle or the capillary orifices while the piston of the pump is at rest. 70

It will be observed that in the construction shown, on account of the stopping of the piston 7 at the end of each stroke, the delivery and the suction of the pump are interrupted during the time the communications are reversed between the channels by the slide-valve 3. During the time the piston is at rest, however, the cylinder-side which received the solution of cellulose under pressure, still receives said solution a given time 80 after the stopping of the piston, in such a manner that the solution of cellulose completely fills the cylinder. As, on the other hand, on account of the stopping of the piston, the tightness of the distributor can be 85 secured by using a slide-valve, having exterior and interior laps, in which the thickness of the parts of the slide-valve separating the distribution chest from the interior channel of the slide-valve (and separating 90 consequently the pressure at the inlet from the pressure at the outlet) is greater than the breadth of the orifices communicating with the cylinder, it will be understood that, notwithstanding the incompressibility of the 95 solution of cellulose, any loss of material will be avoided, thus realizing a volumetric delivery of 100%.

What I claim is:

1. In a pump of the kind described, in 100 combination a cylinder, a piston having a reciprocal movement in said cylinder, a distribution chest, a slide valve having a reciprocal movement in said distribution chest, a rod giving the reciprocal movement to the 105 piston, a block provided with a slot driving said rod, said slot being formed at the ends so as to maintain the piston at rest at the end of each stroke.

2. In a pump of the kind described, in 110 combination a cylinder, a piston having a reciprocal movement in said cylinder, a distribution chest, a slide-valve having a reciprocal movement in said distribution chest, a rod giving the reciprocal movement to the 115 piston, catches keyed on said rod and driving the piston and a block provided with a slot driving said rod, the said slot being provided at each end with parts parallel to the direction of movement of the block, whereby 120 the piston is maintained at rest at the end of each stroke.

3. A plurality of pumps of the kind described, said pumps being arranged coaxially in a line, each of said pumps comprising a 125 cylinder, a distribution chest and a slide-valve having a reciprocal movement in said distribution chest, two rods extending parallel to said pumps, catches keyed on said rods and giving an identical reciprocal 130

movement to the piston and slide-valve of each pump and means whereby the rod driving the pistons of said pumps is maintained at rest at the end of each stroke while the 5 rod driving the slide-valves still moves said slide-valves to reverse the communications in the distribution chest of each pump.

In testimony whereof I have affixed my signature in presence of two witnesses.

ACHILLE DRYEN.
